US00D439486S

(12) **United States Design Patent** (10) Patent No.: **US D439,486 S**
Izumisawa (45) Date of Patent: ** Mar. 27, 2001

- (54) **SQUARE DRIVE WRENCH HAVING ANGLED HEAD**
- (75) Inventor: **Osamu Izumisawa**, Tokyo (JP)
- (73) Assignee: **S.P. Air Kabusiki Kaisha**, Nagano (JP)
- (**) Term: **14 Years**
- (21) Appl. No.: **29/119,378**
- (22) Filed: **Feb. 28, 2000**
- (51) LOC (7) Cl. **08-05**
- (52) U.S. Cl. **D8/70; D8/61**
- (58) Field of Search D8/61-70; 81/57.11, 81/57.13, 57.29, 54, 57.42, 57.39, 469; 173/170, 169, 48, 163, 217, 182; 451/358, 359; 310/50, 240; 433/82, 125

(57) **CLAIM**

The ornamental design for a square drive wrench having angled head, as shown and described.

DESCRIPTION

FIG. 1 is a right side elevation of a square drive wrench having angled head of the present invention;

FIG. 2 is a left side elevation of the wrench;

FIG. 3 is a top plan of the wrench;

FIG. 4 is a bottom plan of the wrench;

FIG. 5 is a front elevation of the wrench; and,

FIG. 6 is a rear elevation of the wrench of the first embodiment.

The broken lines shown in the drawings indicate environmental structure and features which form no part of the claimed design.

1 Claim, 5 Drawing Sheets
